UNITED STATES PATENT OFFICE

113,339

DESIGN FOR AN OVERHEAD AIR CONDITIONING APPLIANCE

Donald P. Wilson, Minneapolis, Minn., assignor
to McQuay, Inc., a corporation of Minnesota

Application November 4, 1938, Serial No. 80,870

Term of patent 7 years

To all whom it may concern:

Be it known that I, Donald P. Wilson, a citizen of the United States, residing at Minneapolis, in the county of Hennepin and State of Minnesota, have invented a new, original, and ornamental Design for Overhead Air Conditioning Appliance, of which the following is a specification, reference being had to the accompanying drawing, forming part thereof.

The single figure of the drawing is a perspective view of an overhead air conditioning appliance, showing my new design. The opposite sides are substantially the same as the sides shown.

I claim:

The ornamental design for an overhead air conditioning appliance, as shown and described.

DONALD P. WILSON.
